(57) **CLAIM**

The ornamental design for a bar table, as shown and described.

DESCRIPTION

FIG. 1 is a front view of a bar table showing my new design; FIG. 2 is a rear view of the bar table of FIG. 1; FIG. 3 is a left side view of the bar table of FIG. 1; FIG. 4 is a right side view of the bar table of FIG. 1; FIG. 5 is a top view of the bar table of FIG. 1; FIG. 6 is a bottom view of the bar table of FIG. 1; FIG. 7 is a perspective view of the bar table of FIG. 1; and, FIG. 8 is a perspective view of the bar table of FIG. 1, shown in an alternate lighted configuration of use.

The broken lines and the areas shown in white overlay within show portions of the bar table that form no part of the claimed design.

1 Claim, 8 Drawing Sheets
